US00D899866S

(12) **United States Design Patent** (10) Patent No.: **US D899,866 S**
(45) Date of Patent: **** Oct. 27, 2020**

(54) **CONTAINER**

(71) Applicant: **YETI Coolers, LLC**, Austin, TX (US)

(72) Inventors: **Dustin Bullock**, Austin, TX (US); **John Loudenslager**, Austin, TX (US); **John Fritz**, Austin, TX (US); **Michael Cieszko**, Austin, TX (US); **Andrew J. Winterhalter**, Austin, TX (US)

(73) Assignee: **YETI Coolers, LLC**, Austin, TX (US)

(**) Term: **15 Years**

(21) Appl. No.: **29/718,915**

(22) Filed: **Dec. 30, 2019**

Related U.S. Application Data

(63) Continuation of application No. 16/218,089, filed on Dec. 12, 2018.

(51) **LOC (12) Cl.** **07-01**

(52) **U.S. Cl.**

USPC **D7/605**

(57) **CLAIM**

The ornamental design for a container, as shown and described.

DESCRIPTION

FIG. 1 is a front, right, perspective view of a container showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depicting the reminder of the container show features that form no part of the claimed design.

1 Claim, 7 Drawing Sheets
